UNITED STATES PATENT OFFICE.

ALVIN C. McCORD AND IVAR A. RANDEL, OF CHICAGO, ILLINOIS, ASSIGNORS TO McCORD AND COMPANY, OF CHICAGO, ILLINOIS, A CORPORATION OF NEW JERSEY.

JOURNAL-BOX.

1,132,370.

Specification of Letters Patent.

Patented Mar. 16, 1915.

Application filed December 20, 1913. Serial No. 807,895.

To all whom it may concern:

Be it known that we, ALVIN C. McCORD and IVAR A. RANDEL, citizens of the United States, residing at Chicago, in the county of Cook and State of Illinois, have invented certain new and useful Improvements in Journal-Boxes; and we do hereby declare the following to be a full, clear, and exact description of the invention, such as will enable others skilled in the art to which it appertains to make and use the same:

Our present invention relates to journal boxes of the type disclosed and broadly claimed in Letters Patent of the United States No. 1,077,159, granted to Ivar A. Randel, of date October 28, 1913, and entitled "Journal box."

The present invention consists in providing the journal box with an independently formed metallic reinforcing and anchoring stirrup that embraces the cellar and is secured to the cellar and to the cast top of the box, in the process of casting, the top fast to the cellar. This reinforcing stirrup not only stiffens the vertical side walls of the cellar but, when provided with lower arch bar bolt holes vertically aligned with bolt holes in the cast top of the box, affords means for very conveniently and securely bolting and anchoring the box to the top and bottom arch bars, and tie bars.

In the accompanying drawings, which illustrate the invention, like characters indicate like parts throughout the several views.

Referring to the drawings:—Figure 1 is a view partly in plane and partly in horizontal section on the line $x^1 x^1$ on Fig. 3; Fig. 2 is a vertical section taken on the irregular line $x^2 x^2$ on Fig. 1; Fig. 3 is a view partly in outer end elevation and partly in vertical section on the line $x^3 x^3$ on Fig. 1; and Fig. 4 is a detail in horizontal section taken on the line $x^4 x^4$ on Fig. 3.

The independently formed cellar 1, which is preferably pressed into shape from sheet steel, is, as shown, formed with an integral rear end or outside dust guard wall 2 having the usual large axle passage 3. An independently formed inside dust guard wall 4 is also advisably constructed from sheet steel and is preferably provided with flanges 5 on its bottom and vertical edges. This inside dust guard wall is also provided with the usual large axle passage. To

adapt the cellar to receive the dust guard, not shown, between its inside and outside dust guard walls, its inner end portion is slightly expanded, thereby forming stop shoulders 1^a, against which the inside dust guard wall 5 is arranged to be seated, when it is placed in working position, as shown in the drawings.

The cellar 1 is shown as provided with a rounded bottom, and the intermediate portions of its vertical walls, and also the lower portion of the bottom thereof, are formed with inwardly pressed channels that are adapted to receive the vertical prongs and the horizontal bottom bar, respectively, of independently formed metallic stirrup 6. The upper ends of the prongs of the stirrup 6 extend approximately to the upper edges of the sides of the cellar. Preferably, this stirrup 6 is formed from a sheet of thin bar steel bent upon itself into rectangular form, with double folded portions 6^a projecting from the bottom bar beyond the vertical prongs thereof. These projecting portions 6^a are formed with tie bar bolt holes 7, and, preferably, the vertical prongs of the said stirrup 6 are formed with longitudinally extended inwardly pressed corrugations that fit correspondingly inwardly pressed portions of the cellar. The corrugations just noted stiffen both the prongs of the stirrup and sides of the cellar and permit the bolts, not shown, to be applied very close to the cellar.

When the cellar and yoke 6, together with the inside dust guard wall 5, where the latter is employed, have been properly positioned and presented to the mold or flask provided for casting of the top, the molten metal in forming the top 8 is poured into the mold cavity, and the top is thus cast fast to the upper edge of the cellar and to the upper ends of the prongs of the yoke, and to the upper edge of the inside dust guard wall. In this way, the component parts of the journal box are permanently and very rigidly united. In fact, when thus united by the top, the above noted elements of the box are connected by substantially integral joints which do not permit of any initial relative movements of the elements, and can not be loosened up or separated by the constant and severe jars and pounding action to which they are subjected in service. The cast top 8 is provided with upper arch

bar bolt holes 9 that are vertically alined with the lower tie bar bolt holes 7 in the stirrup 6; and between its outside and inside dust guard walls, it is formed with an elongated dust guard passage 10 which permits the dust guard, not shown, to be properly inserted into the box.

Preferably, we employ the means disclosed in the application of Ivar A. Randel, S. N. 795,513, filed October 16, 1913, and entitled "Journal box," for making the upper edge of the cellar and of the inside dust guard wall abnormally contractible, and for causing the same to interlock with the cast metal of the top in the process of casting the top onto the cellar.

What we claim is:—

1. A journal box comprising an independently formed metallic cellar, an independently formed metallic stirrup embracing said cellar, and a top made fast to said cellar and stirrup by the metal of said top in the forming thereof.

2. A journal box comprising an independently formed pressed steel cellar, an independently formed pressed steel stirrup having upturned prongs embracing the sides of said cellar, and a top cast fast to the upper edges of said cellar and to the upper ends of the prongs of said stirrup.

3. A journal box comprising an independ-

ently formed press steel cellar, an independently formed pressed steel stirrup having upturned prongs embracing the sides of said cellar, a top cast fast to the upper edges of said cellar and the upper ends of the prongs of said stirrup, and having projecting portions with bolt holes therein, the lower horizontal portion of said stirrup being bent upon itself and extending below the bottom of said cellar and having projecting portions with bolt holes vertically alined with the bolt holes in said top.

4. A journal box comprising a sheet metal cellar, an independently formed pressed steel stirrup having its upwardly projecting prongs set into channels formed in the sides of said cellar and bent upon itself to form bottom projections, which latter are provided with bolt holes, and a top cast fast to the upper edge of said cellar and to the upper ends of the prongs of said stirrup, and having bolts vertically alined with the bolt holes in the projecting portions of the stirrup.

In testimony whereof we affix our signature in presence of two witnesses.

ALVIN C. McCORD.
IVAR A. RANDEL.
